US00D488960S

(12) **United States Design Patent** (10) Patent No.: **US D488,960 S**
Wahl et al. (45) Date of Patent: ** Apr. 27, 2004

(54) **STANLEY BOLT VACUUM BOTTLE**

(75) Inventors: **Andrew C. F. Wahl**, Seattle, WA (US);
Gary A. Hurlbut, Seattle, WA (US)

(73) Assignee: **Pacific Market, Inc.**, Seattle, WA (US)

(**) Term: **14 Years**

(21) Appl. No.: **29/178,852**

(22) Filed: **Mar. 31, 2003**

(51) LOC (7) Cl. **07-01**

(52) U.S. Cl. **D7/608**

(58) Field of Search D7/605-608, 312-322;
D9/500, 503, 504, 538; 62/457.1-457.7;
